(57) **CLAIM**

The ornamental design for a shower rod curtain guide as shown and described.

DESCRIPTION

FIG. 1 is a side view of a shower rod curtain guide showing my new design;

FIG. 2 is another side view thereof, showing my new design, shown with environment;

FIG. 3 is an enlarged front view of the shower rod curtain guide;

FIG. 4 is an enlarged back view thereof;

FIG. 5 is an enlarged partial view of the selected portion shown in FIG. 1;

FIG. 6 is an opposing side view thereof; and,

FIG. 7 is a cross-sectional view thereof, taken along the line 7-7 of FIG. 5.

The broken line showing of FIG. 2 is for the purpose of illustrating environmental structure and forms no part of the claimed design. The broken line showing of a circular shaped selection annotation in FIG. 1 and the broken line showing of symbolic break lines in FIGS. 1, 5, and 6 are for the purpose of indicating partial view and form no part of the claimed design.
